INK-REGULATING MECHANISM FOR EXTENDED-DELIVERY DEVICES OF PRINTING PRESSES.

Application filed March 5, 1925. Serial No. 13,344.

It has become common practice to provide a sheet pile table or delivery table to receive the sheets from printing presses, set off at the front of the press where the pile table 5 can have a much greater vertical downward movement in order to receive a large number of sheets before the pile table has to be emptied. This extended pile table comes in front of the keys by means of which the 10 adjustment is made for the proper distribution of ink on the fountain roller of the press, and provision must be made for operating these ink adjusting keys; and one method has been to set the pile table off from 15 the press sufficiently to permit the operator to reach in or to get in between the fountain keys and the pile table to adjust the keys. The object of my present invention is to provide for remote control of the fountain keys by arranging upon or adjacent to some part of the pile table support means by 20 which fountain keys may be operated from a remote position upon the pile table device. With this remote control it is possible for 25 the operator to adjust the fountain keys without the operator having to reach in between the press and the extended delivery device. Therefore space need not be specially provided between the extended pile 30 table device and the fountain keys but these two may be placed as close as desired.

Another advantage in the present arrangement is that while the operator is adjusting the fountain keys by means of the remote 35 control he can at that time stand in a position where he can readily see the printed surface of the sheets as they are delivered from the press upon the extended pile table, in order to observe whether the ink supply 40 should be increased or decreased on the printed sheets and in order to observe the effect of each adjustment of keys upon the printed sheets as they come from the press following each adjustment of the fountain 45 keys. Heretofore, where the operator was obliged to get in between the fountain keys and the extended delivery to adjust the keys, he had to take with him a printed sheet as a guide in making the adjustments of the 50 keys and then he was obliged to step out and take another sheet coming from the press to observe the effect of the adjustment of the keys. It will be obvious that in adjusting a number of such keys the operator may be

obliged to step in between the keys and extended delivery a great many times in order to arrive at the proper distribution of ink, all of which may be avoided by the use of the present invention.

Another object of my invention is to provide for a remote fountain key control carried by the extended delivery device which may be bodily moved with the latter whenever it is rolled out on the floor away from the press, so that the extended delivery device and the remote key control may be bodily moved as a unit.

Another object of my invention is to provide a remote control which will operate as near as possible the same as if the operator 70 operated the fountain keys direct. This is an advantage because in many cases the operator depends on the sense of feel of the fountain keys in judging exactly how much a key should be turned in order to increase or decrease the supply of ink controlled by an individual key.

My invention I believe to be broadly new in that it is the first remote control for fountain keys arranged on an extended delivery device and in the drawings I have shown two embodiments of the broad idea intending, however, to cover all forms which come within the scope of the claims herein.

In the drawings forming part of this application,

Figure 1 is a side elevation of an extended delivery device arranged at one end of the printing press and showing one form of my improvements applied thereto,

Figure 2 is a plan view of the parts shown in Figure 1,

Figure 3 is a view corresponding with Figure 1 but showing the parts in a different position,

Figure 4 is a detailed elevation of one branch of the adjusting mechanism showing the parts on an enlarged scale in the same position as they appear in Figure 1,

Figure 5 is an enlarged view of the same parts as is shown in Figure 4 but looking at them in the same position as they appear in Figure 2,

Figure 6 is a side elevation on a large scale of part of the remote control devices 105 showing the parts in the same position as in Figure 1,

Figure 7 is a plan view of part of the re-

remote control device corresponding with the position shown in Figure 2,

Figure 8 is a similar view of a modified form of device for controlling the operation 5 of the adjusting shaft,

Figure 9 is a side elevation of an extended delivery device showing a modified form of remote control of the fountain keys,

Figure 10 is a plan view of the parts 10 shown in Figure 9,

Figure 11 is a sectional view of a floor plate for use with this form of my invention, and

Figure 12 is a detailed view of the fountain keys in this form of the invention.

My invention requires no particular modification of the extended delivery device and by way of illustration I have shown my invention applied to the well known Babcock 20 extended delivery device without intending to limit my invention to this application.

In the drawings I have shown only the 25 end of the printing press at 170 as it is only necessary to show the ink fountain roller in order to teach the application of my invention. I have shown the usual ink fountain 171 together with the fountain roller 172 which receives ink from the fountain and transmits it to the doctor roller, not shown, all of which operates in the usual manner. The scraper or ink blade indicated at 173 is of the usual type and it serves to regulate the amount of ink taken by the fountain roller. This blade, which is usually of very thin metal, so that it may be individually flexed by each fountain key 30 is directly actuated by a series of bell-crank levers 174 disposed across the press and adapted to press on the ink blade 173. For 35 each bell-crank lever there is a key 29 screw threaded into its support and adapted to press on one of the arms of the bell-crank lever 174 to adjust the pressure of the latter against the ink blade 173. Each key usually has a flat finger grip by means of which the key may be turned to the right or left for the purpose of increasing or decreasing the pressure of the ink blade upon the fountain roller. All of the parts just 40 described are of the usual construction as found on most flat bed printing presses.

The extended delivery device used to illustrate my invention consists of the posts 45 175 which support the upper frame members 176 and on the latter there are mounted sheaves 177 over which the cables 178 travel and these cables are provided with suitable tackle 179 on their depending ends which support the vertically movable pile table 50 180 which receives the sheets as they are delivered from the printing press. Further details of the extended delivery device need not be set forth herein but it may be pointed out that the extended delivery device may 55 be made to be bodily moved toward and

from the press, being shown in operative relation to the press in the several views of the drawings.

Referring to the form of my invention shown in Figures 1 to 7 inclusive the device 70 consists of the following: There is a shaft 21 extending crosswise of the extended delivery and it is journaled at 22 and 23 in the frame of the extended delivery device. Pivoted on the shaft 21 are the angle levers 75 24 and 25 one at each side and outside the frame of the extended delivery. These levers are connected together by means of shafts 26, 27 to cause them to move together 80 and I prefer to screw the levers 24, 25 to the shaft 21 or otherwise fix them thereto in order that the several parts will rock as a unit from the shaft 21 as the axis. At 85 28 I have shown a shaft extending crosswise of the delivery frame and it lies in front of the several fountain keys 29 when in operative position and this shaft is free to rotate in the levers 24, 25 in which it has its bearings. There is a yoke 30 through 90 the arms of which the shaft 28 extends. As shown in Figure 4 the yoke 30 has a pair of upwardly extending arms which have a fork 181 straddling the shaft 26 to hold the yoke from turning upon the shaft 28 and this yoke is adapted to slide along the shaft 28. There is a bevel gear 31 keyed to the shaft 28 and movable with the yoke 30. This bevel gear meshes with and drives a bevel gear 32 which is attached to and revolves the fork 33 which latter is adapted to 95 engage any one of the fountain keys 29 across the press according to the position in which this yoke is placed as will appear hereinafter.

At the extreme front end of the levers 100 24, 25 there is a cross shaft 34 which is adapted to revolve in these levers and it is provided with a number of markings 47 corresponding in position with the location of the individual fountain keys 29. In Figures 6 and 7 I have shown in detail the parts 105 for revolving the shaft 34. There is a key 39 as indicated in Figure 6, or a knurled nut 39 as shown in Figure 7 on a shaft passing through the yoke 36 which slides on the 110 shaft 34. The extended arms 182 of this yoke engage the shaft 27 to prevent the yoke from turning on the shaft 34. The yoke 36 is provided with a pointer 48 which cooperates with the markings 47 on the shaft 115 34 by means of which the yoke 36 may be accurately positioned to bring the fountain key fork 33 in position to engage any one of the individual fountain keys. On the shaft which carries the key 39 there is a 120 bevel gear 38 which operates a bevel gear 37 keyed to the shaft 34. This bevel gear 37 is free to slide along the shaft 34. It will be apparent that if the key 39 of the 125 remote control device is turned to the right 130

or left that the motion will be transmitted through the gears 38 and 37 to turn the shaft 34.

There is a shaft 40 mounted in the swivel bearings 45 and 46 for transmitting the motion from the shaft 34 to the shaft 28. On the shaft 34 there is a spiral gear 44 which operates the spiral gear 43 on the shaft 40 to revolve the latter. On the other end of the shaft 40 there is a spiral gear 41 which operates the spiral gear 42 on the shaft 28 whereby the motion is imparted to the latter shaft for revolving the fork 33.

I provide means for shifting the yoke 30 and its fork 33 crosswise of the press in order to engage this fork with any of the several fountain keys 29 of the press. For this purpose I have shown a wire cable 183 attached to one arm 182 of the yoke 36 at 49 and this cable extends to the right in Figure 2 and passes around a sheave 51 and from there it passes to the rear and around a sheave 52 and then it extends across the delivery frame and passes around a sheave 53, and the other end of this cable is connected with the yoke 30 at 54. Another cable, 184 is connected with the other arm 182 of the yoke 36 at 50 and this passes to the left in Figure 2, thence around the sheave 185 and thence to the rear and around the sheave 186, thence across the delivery frame and around the sheave 187 and the free end is connected with the yoke 30 at 55. It will be apparent from these connections that if the yoke 36 is moved either to the right or to the left along the shaft 34 that the motion will be imparted through the cables 183, 184 to the yoke 36 and to the same extent so that by moving the yoke 36 the yoke 30 may be brought into line with any one of the fountain keys 29.

Operation.

The operator will observe the printed sheets as they are delivered upon the pile table 180 and having determined whether adjustment of the ink distribution is necessary, he proceeds as follows: The entire frame including the levers 24, 25 and the cross shafts 26, 27, and 34 is rocked on the shaft 21 to lift the forward end of this frame as shown in Figure 3, or to any other lesser degree sufficient to move the forks 33 out of the path of the several fountain keys 29. While the frame is thus lifted up, the yoke 36 is moved along the shaft 34 until the pointer 48 registers with one of the marks 47 on the shaft 34, corresponding with the fountain key which the operator desires to adjust, and this moves the yoke 30 crosswise of the press to bring the fork 33 opposite the fountain key selected. The swinging frame is then lowered until the adjusting screw 189 rests on the lug 190 and while the frame is being

swung back into position the key 39 is turned so that the fork 33 straddles the selected fountain key 29. While the yoke 36 was being adjusted along the shaft 34, the cables 183, 184 transmitted the motion to 70 the yoke 30 so that the latter moved in the same direction and to the same extent upon the shaft 28 as the yoke 36 moved on the shaft 34.

The frame having been swung back into 75 position with the fork 33 straddling one of the fountain keys 29, the operator will now turn the key 39 for the purpose of increasing or decreasing the supply of ink on the fountain roller at some particular location, corresponding with the particular fountain key 29 which is being adjusted. The turning of the key 39 rotates the mitre gear 38 which acts on the mitre gear 37 to rotate the shaft 34, the direction of rotation 80 being determined by the direction of rotation of the key 39. The movement of the shaft 34 is transmitted through the bevel gears 44 and 43 to the shaft 40 and the latter transmits the force through the bevel gears 41 and 42 to the shaft 28; and from the latter the operating force is transmitted through the bevel gears 31 and 32 to the fork 33 which actuates the fountain key 29. By proper designing of the parts the fork 95 33 may be caused to turn the same extent as the key 39 and the "feel" of the key 39 may be made to correspond very closely to the "feel" when the fountain keys 29 are operated directly by hand.

It will be apparent that the pile table structure may be moved bodily away from the printing press whenever that is desirable and the present mechanism will move bodily with the pile table structure so that the operator may get at any of the parts at the forward end of the printing press. When the pile table structure is about to be returned into position adjacent the press, it is advisable to move the yoke 36 to a 100 position intermediate any two of the markings 47 in order that the fork 33 will be out of alignment with the fountain keys 29; or else the frame which includes the levers 24, 25 should be raised as shown in Figure 3 105 110 while the pile table structure is being moved back into place. The shaft 40 is preferably arranged at one side of the pile table frame so that the pile of sheets may be moved away upon a suitable truck from the opposite side of the pile table frame; and it will be apparent that the shaft 40 may be disposed at either side of the frame to permit the pile to be moved from either the right or left side.

I have described the method of operating the device to adjust one of the fountain keys 29 and it will be understood that the frame 24, 25 may be raised and the yoke 36 may be adjusted in the same manner to 125 130 135

engage the fork 33 with any of the other fountain keys 29.

In Figure 8 I have shown another means for rotating the shaft 34. This consists of 5 a yoke 59 sliding on the shaft 34 and having arms 191 straddling the shaft 27 to prevent the yoke from rotating on the shaft 34. Between the arms of this yoke there is a 10 knurled hand grip 60 which is keyed to the shaft 34 so that the grip 60 may slide along this shaft and so that it can rotate the shaft. The pointer 192 carried by the yoke 59 cooperates with the markings 193 on the shaft 27 to indicate the positions of the several 15 fountain keys 29. The cables 183, 184 will be connected with this yoke 59 the same as they are connected with the yoke 36 in the first form, so that the only difference is in the method of revolving the shaft 34. This 20 is accomplished by turning the hand grip 60 in either direction.

The frame which includes the levers 24, 25 may be raised to such an extent that the operator may reach in and adjust the fountain keys 29 directly by hand if that is desirable and it will be apparent that the press may be operated no matter what position this frame may be in at any time.

In Figures 9, 10, 11, and 12 I have shown 30 a modified form of my invention. In this form I have provided an extra arm 194 on each bell-crank lever 63 the usual arm 195 being operated by ordinary fountain keys 64. A cable 66 attached to the extra arms 35 194 of the lever 63 is adapted to operate this lever the same as if operated by the fountain keys 64. There will be a cable 66 for each lever 63 and these will extend downwardly and around the several sheaves 40 67, close to the floor, mounted on the cross shaft 196. From there the cables 66 pass horizontally to the rear of the pile table frame and thence around the series of sheaves 68 which are freely revolvable upon 45 a cross shaft 197 and at 198 the several cables extend upwardly to the upper portion of the table frame. On a cross shaft 70 I have arranged the small bell-crank levers 69 for each of the cables 66 and one end 50 of each cable is secured to a lever 69 at the point 199. The arm 200 of each lever 69 is adapted to be acted upon by a key 71 in the same manner that the ordinary key 64 operates on the bell-crank lever 63. If the key 71 is turned so that it presses to the right on the arm 200, the motion will be transmitted through one of the cables 66 and the bell-crank lever 63 will be caused to press 55 against the fountain blade 173 exactly the same as if the key 64 were turned directly by hand. When the key 71 is slackened off, the tension of the fountain blade 173 causes the cable 66 to be drawn so that the lever 69 follows the key 71. In this form of the 60

invention the feel or touch of the keys 71 65 will correspond very closely to the feel or touch experienced when operating the ordinary keys 64 direct. In order to protect the several cables 66 where they pass across the floor, I provide a bridge or plate 201 70 resting on the floor and having grooves or slots 202 in its under side through which the cables 66 pass and this plate may be permanently fastened to the floor. The truck used for removing the pile of sheets 75 may run freely over this plate.

From the above it will be apparent that I have provided a remote control for the fountain keys of a printing press mounted upon the extended delivery device to permit adjustment of the fountain keys without getting into the space between the press and the extended delivery. While I have shown the controlling members of the remote control arranged at the front of the extended 85 delivery I do not wish to limit my invention to this arrangement as it will be obvious that the controlling elements could be arranged at some other position on the extended delivery. Neither do I wish to be understood 90 as limiting my invention to the particular forms of devices shown and described herein. I believe I am the first to provide a remote control arranged on the extended delivery 95 device.

Having described my invention, what I claim is:

1. The combination with a press having inking mechanism associated therewith, an extended delivery device set off at the end of 100 the press and including a frame and a raising and lowering pile table thereon, and a remote control for said inking mechanism mounted on said delivery frame.

2. The combination with a press having 105 inking mechanism associated therewith, including separately operable members for controlling the distribution of ink, an extended delivery device set off at the end of the press and including a frame and a rising 110 and falling pile table and remote control means mounted on said extended delivery device frame for individually controlling said separately operable members.

3. The combination of a press having ink- 115 ing mechanism, an extended delivery device set off near the end of the press and movable toward and from the press, and remote controlling means for said inking mechanism, mounted on said extended delivery device and movable therewith toward and from the press.

4. The combination of a press having 120 inking mechanism associated therewith, an extended delivery device set off adjacent the end of the press and comprising a frame and a rising and falling pile table and remote control means arranged on the forward end 125

of said delivery device frame for controlling the distribution of ink in said inking mechanism.

5. The combination of a press having ink mechanism including ink distributing means, an extended delivery device set off at the end of said press and including a vertically moving pile table and a supporting frame, and remote controlling means for said ink distributing means, arranged at the forward end and at the upper part of said table support.

6. The combination of a press having ink mechanism including ink distributing means, 15 an extended delivery device set off near the end of said press and including a vertically moving pile table and a supporting frame, and remote controlling means arranged at the forward end of said table support for controlling said ink distributing means, and transmitting means for said remote control, extending around the path of travel of said pile table.

7. The combination of a press having 25 inking mechanism associated therewith and including a plurality of keys for controlling the distribution of ink, an extended delivery device set off at the end of the press and including a frame and vertically moving pile 30 table and remote control means mounted on said extended delivery frame and adapted to individually operate said keys.

8. The combination of a press having inking mechanism, a plurality of keys for controlling the distribution of ink, an extended delivery device set off near the end of the press and including a frame and a vertically moving pile table, remote control means mounted on said extended delivery frame, 40 means for connecting said remote control device with any of said fountain keys for individual operation of the latter.

9. The combination of a press having ink mechanism including fountain keys for controlling the distribution of ink, an extended delivery device set off near the end of the press and including a supporting frame, a guiding member mounted on said frame, a sliding member movable on said guiding member, and means for connecting said sliding member with any of the individual fountain keys whereby said sliding member may be caused to operate any of the several fountain keys.

55. 10. The combination of a press having ink mechanism including fountain keys for controlling the distribution of ink, an extended delivery device set off near the end of the press and including a frame, a guide member supported on said frame, sliding means on said guide member, and means for indicating the position of said sliding means in relation to the fountain keys, and means for connecting said sliding means with the individual fountain keys for effecting the operation of the latter.

11. The combination of a press having ink mechanism including fountain keys for controlling the distribution of ink, an extended delivery device set off near the end of the press and including a frame, rocking supports mounted on said frame and a fork adapted to be engaged with any of the several fountain keys by the operation of said rocking support, a guide member carried by said rocking support, sliding means on said guide member, means for transmitting the movements of said sliding means to said fork, said sliding means including means for revolving said fork to operate the fountain keys.

12. The combination of a press having ink mechanism including fountain keys for controlling the distribution of ink, an extended delivery device set off at the end of the press, a rocking support, a shaft thereon, a laterally moving fork on said shaft adapted to engage with any of said fountain keys, a second shaft carried by said rocking support, sliding means on said latter shaft adapted to revolve said latter shaft, means operated by said sliding means for shifting said fork to cause it to engage any of said fountain keys, and means for transmitting the movement of said second shaft to said first shaft.

13. The combination of a press having ink mechanism including fountain keys for controlling the distribution of ink, an extended delivery device set off adjacent said press, 100 a rocking support carrying a shaft, a fork sliding on said shaft and adapted to engage any of said fountain keys, gears interposed between said shaft and said fork for operating the latter, said fork being adapted to be engaged and disengaged with a fountain key by the operation of said movable support, a second shaft on said movable support, sliding means mounted on said second shaft and having means for revolving the latter, 110 means for transmitting the movement of said second shaft to said first shaft and flexible members connecting said sliding means and said fork whereby the sliding movement of said sliding means will be transmitted to said fork to align the latter with any individual fountain key.

14. The combination with a press having an ink fountain, primary fountain keys for regulating the ink, and a remote control device for said keys, including a member adapted to be shifted in position to engage any of the several primary keys, a shaft, a secondary key shiftable along said shaft and adapted to revolve said shaft, means for transmitting the shifting motion of said secondary key to the member which engages the primary keys and means for transmitting

the revolving motion of said shaft to the particular primary key engaged by said first member.

15. The combination of a press having an ink fountain, primary fountain keys, a shaft, an operating member shiftable on said shaft in position to engage any of said primary keys, a second shaft spaced from said first shaft, a secondary key and means for guiding the same on said shaft, means for transmitting the shifting motion of said secondary key to said engaging member for the purpose of selecting any primary key for operation, means whereby said secondary key may revolve said second shaft, and means for transmitting the motion of said second shaft to said engaging member for the purpose of operating a primary key.

16. The combination of a press having an ink fountain, primary fountain keys, a shaft, an operating member shiftable on said shaft in position to engage any of said primary keys, a second shaft spaced from said first shaft, a secondary key and means for

guiding the same on said shaft, means for transmitting the shifting motion of said secondary key to said engaging member for the purpose of selecting any primary key for operation, means whereby said secondary key may revolve said second shaft, means for transmitting the motion of said second shaft to said engaging member for the purpose of operating a primary key, and a swinging frame on which said engaging member and said shafts are mounted to be swung in relation to said primary keys.

17. The combination with a press having ink mechanism, an extended delivery device set off near the end of the press and movable toward or from the press, and remote controlling means for said inking mechanism, mounted at the outer end of said extended delivery device and movable toward or from the press.

Signed at the city and county of New London, and State of Connecticut, this 5th day of December, 1923.

FRED S. ENGLISH.
